UNITED STATES PATENT OFFICE.

JOSEPH LAFRANCE, OF MONTREAL, QUEBEC, CANADA, ASSIGNOR OF ONE-HALF TO
ONESIME LAFRANCE, OF MONTREAL, CANADA.

JACK.

1,362,630.

Specification of Letters Patent. Patented Dec. 21, 1920.

Application filed February 24, 1920. Serial No. 360,797.

To all whom it may concern:

Be it known that I, JOSEPH LAFRANCE, a British subject, manufacturer, residing at 10 St. Jerome St., in the city of Montreal, in the Province of Quebec, in the Dominion of Canada, have invented certain new and useful Improvements in Jacks; and I do hereby declare that the following is a full, clear, and exact description of the same.

10 The present invention relates to jacks particularly adaptable to automobiles and the like, and the main object of this invention is to provide a device of this character that will be strong, easily operated and simple 15 and cheap of construction.

Another object is to provide a device of this character with movable cantaliver arms, which exert an even pulling or pushing action on both sides of the jack, thus raising 20 evenly the lifting head.

A further object is to provide a device of this character which will eliminate the ratchet and toothed racks in jacks.

To understand the invention reference 25 will be had to the accompanying drawings in which—

Figure 1 is a side elevation of a jack according to the invention, illustrated in its unraised position.

30 Fig. 2 is a side elevation showing the jack in its raised position.

Fig. 3 is an elevation from the other side of a jack, two of the cantaliver arms having been removed to disclose the central slot 35 through which passes the worm.

Fig. 4 is an enlarged sectional view through one of the connecting members, in which is journaled the unthreaded portion of the worm shaft.

40 Fig. 5 is an enlarged sectional view through the other connecting member which is provided with a thread to engage the worm shaft.

Fig. 6 is a side elevation of an extension 45 handle to be applied to the worm shaft.

Like numerals of reference indicate corresponding parts in each figure.

In the drawings—

1 is a base plate having intermediate 50 thereof an upright or post 2 provided with a plurality of holes 3. Fitted over said post 2 is a hollow member 4 which is provided

with a hole 5, and 6 is a pin which is inserted through said hole 5 and through one of the holes 3 in order to adjust the height 55 of said member 4.

Provided in the upper end of said hollow member is a lifting head 7 having a depending stem 8 which has at its lowermost end, a slot 9 to permit the free passage there- 60 through of a worm shaft 20 that will be described further.

Intermediate of the hollow member 4 is a slot 10 which corresponds to the slot 9 in the stem 8 and serves the same purpose. 65 The lowermost end of the hollow member 4 is provided with two socket members 11, on each side thereof, and 12 are socket members provided on each side of the lifting head 7 in which are pivotally secured the cantaliver 70 arms or links 13 by means of the pins 14. The other ends i. e., the converging ends of the links 13 are pivotally secured to the connecting socketed members 15 and 16 by means of pins 17.

75 The socketed member 15 is provided centrally with an unthreaded hole 18, and the member 16 has a threaded hole 19. 20 is a worm shaft provided with a crank handle 21 at one end, and 22 is a shoulder adapted to 80 rest against the socketed member 15. The said worm shaft projects through the hole 18, the slot 10 in the member 4, the slot 9 in the stem member 8 and threads into the threaded hole 19 in the socketed member 16. 85

It will readily be seen that when the handle 21 is turned, the shoulder 22 will rest on the member 15 and will carry said member inwardly, while at the same time the worm shaft 20 will engage the threaded hole 90 19 and pull inwardly the socketed member 16. As the members 15 and 16 are made to travel inwardly and as the cantaliver arms or links 13 are hingedly secured to the socketed members 11 and 12 on the hollow mem- 95 ber 4, and the head 7, the result is that said links will lift the head 7, as the links are gradually brought practically into a vertical line, thus providing a most powerful lifting jack.

100 It will be noted that before the jack is operated, the hollow member 4 is adjusted on the base by means of the pin 6, which is inserted in the holes 5 and 3.

To lower the jack, the handle is turned in

the opposite direction and as already described, the weight on the lifting head will cause the links to regain their oblique primitive position, as the socketed members gradually move away from the hollow member 4.

The handle 21 is removable from said worm shaft, in order to collapse the device into compact form when not in use.

In Fig. 6 of the drawings is disclosed an extension arm 23 provided at one end with a brace handle 24, the other end of said arm being adapted to engage the universal joint 25 which is provided at the end of the worm shaft 20. It will readily be understood that the extension arm 23 when used in connection with the worm shaft will enable a person to operate the jack at a distance, from under the machine.

What I claim as my invention is:—

1. A jack comprising, in combination, a vertical main member; a vertical lifting member telescopically and slidably related thereto and having a head at its upper end, said main and lifting members being provided with registering vertical slots; a pair of links pivoted at their upper ends to the opposite sides of said head; a pair of links pivoted at their lower ends to the lower end of the main member at opposite sides thereof; a pair of connecting members to which the mutually-adjacent ends of the corresponding first- and second-named links are pivoted, each connecting member having a hole formed centrally and transversely 35 through it; a horizontal operating shaft extending through the registering slots in said main and lifting members and journaled in

the holes in said connecting members, and means for rotating said shaft.

2. A jack comprising, in combination, a base; a vertical post thereon; a hollow main member fitted over said post; said main member and said post constituting companion parts, one of which is provided with a plurality of superposed openings, and the other of which is provided with a single opening for interchangeable registration therewith to adjust the position of the main member upon the post; a fastening device removably engaged in said registering openings to retain said main member in adjusted position; a pair of links pivoted at their lower ends to the lower end of the main member at opposite sides thereof; a vertical lifting member telescopically and slidably related to the upper portion of the main member and provided at its upper end with a head, said lifting and main members being formed with registering vertical slots; a pair of links pivoted at their upper ends to the opposite sides of said head; a pair of connecting members to which the mutually-adjacent ends of the first- and second-named links are pivoted; and an operating shaft extending horizontally through 60 said registering slots and journaled in said connecting members.

Signed at Montreal, Quebec, Canada, this 9th day of February, 1920.

JOSEPH LAFRANCE.
